UNITED STATES PATENT OFFICE

HERMAN H. DIEHL, OF HUNTINGTON, WEST VIRGINIA, ASSIGNOR TO THE WEST VIRGINIA RAIL COMPANY, OF HUNTINGTON, WEST VIRGINIA, A CORPORATION OF WEST VIRGINIA

RAILWAY-TRACK CONSTRUCTION

Application filed April 30, 1928. Serial No. 273,981.

My invention relates more particularly to the switch equipped portion of railway track construction and more especially to constructions wherein the switches are provided as 5 portable structures for assembly with a main track at any desired point thereon such constructions being of particular utility in railway track installations in mines.

One of my objects is to provide a novel, 10 simple, and relatively inexpensive construction of switch mechanism which may be quickly applied to the rails of a main track at any desirable location thereon and repositioned in different locations as desired, 15 without disturbing the position of the main rails and the continuity thereof.

Another object is to provide in a switch construction, of the general character above referred to, and in which the wheels upon 20 engaging the switch track are raised to clear the main rail on the turnout side, against derailment of the wheels in passing from the main track onto the switch track and travelling along the latter.

25 Another object is to provide in a switch construction of the character above stated, a frog device forming a part of the switch structure at the main rail on the turnout side which may be quickly assembled with the 30 main rail and disassembled therefrom, and when assembled therewith be rigidly held in place on the main rail.

Another object is to provide a switch structure the portion of which at the turnout side 35 of the main track is so constructed that the wheels of a car in passing along the switch track will be properly guided against derailment and in passing along the switch track and over the main rail at the turnout 40 side will be subjected to the minimum of jarring action.

Another object is to provide a switch structure of the character above referred to which shall be so constructed that cars provided 45 with wheels having broad flat treads or cars provided with caterpillar tractor bars may move along the main track without obstruction from the cross-over portion of the switch track.

50 Another object is to provide a frog, as a

part of the switch structure, of such form that clips of the same form and size as those used for holding the rail portions of the switch structure to the ties may be used for securing the frog in place on the ties of the 55 switch, thereby avoiding the necessity of providing different means for securing the frog in position; and other objects as will be manifest from the following description.

Referring to the accompanying drawings:—

Figure 1 is a plan view of a track layout provided with a switch track embodying my invention.

Figure 2 is an enlarged section taken at the 65 line 2—2^a on Fig. 1 and viewed in the direction of the arrow.

Figure 2^a is a broken view in side elevation of a portion of the track structure at one of the switch terminals.

Figure 3 is a plan view of one of the sections of a jumper frog forming a part of the structure of Fig. 1, the main rail and one of the switch rails being shown, by dotted lines, 70 assembled therewith.

Figure 4 is a similar view of another section of the frog showing, by dotted lines, the switch rail connected therewith.

Figure 5 is a broken enlarged sectional view taken at the line 5 on Fig. 1 and viewed 80 in the direction of the arrow.

Figure 6 is an enlarged sectional view taken at the line 6 on Fig. 1 and viewed in the direction of the arrow.

Figure 7 is an enlarged sectional view 85 taken at the line 7 on Fig. 1 and viewed in the direction of the arrow.

Figure 8 is a sectional view taken at the line 8 on Fig. 1 and viewed in the direction 90 of the arrow; and

Figure 9, an enlarged, broken, sectional view taken at the line 9 on Fig. 1 and viewed in the direction of the arrow.

The rails of a main track to be equipped with the switch device, are represented at 10 and 11, these rails being secured in the desired gaged condition, by any suitable means (not shown).

The switch track comprises the rails 12 and 13, the rail 12 comprising the terminal 100

rail section 14, a rail section 15, and a rail section 16, the rail sections 15 and 16 being spaced apart and lying at opposite sides of the main rail 11. The rail 13 comprises a 5 terminal rail section 16 and a rail section 17.

The terminal rail sections 14 and 16 extend adjacent corresponding sides of the main rails 10 and 11 and are connected together by a connecting bar 18 through the medium 10 of which they may be swung into and out of switching position, as by means of switch throwing mechanism represented at 19 and which may be of any desirable construction, these terminal rail sections being supported 15 in any desirable way at the ends thereof opposite their terminal portions to permit of their movement into the out-of switching position.

The rail sections 14 and 16, by way of example, and preferably, are of the same cross sectional shape as the ordinary railway rail with their terminal portions slightly deflected laterally as shown at 20 and 21, respectively, and machined along their sides and with their 25 heads undercut to lie flatwise against the sides of the main rails 10 and 11 and overlie the tread portions of these main rails.

The switch structure also comprises a frog represented generally at 22 and interposed 30 in the space between the rail sections 15 and 16, and a guard rail section 23 located at the inner side of, and in spaced relation to, the rail section 17 directly opposite the frog 22.

It may be here stated that the frog 22 is of 35 such construction that the bearing surface provided thereby for the wheels in passing over it extends at such an elevation as to avoid grooving the main rail 11 at the frog, or otherwise providing for the reception of the 40 flanges of the wheels.

In accordance with my invention the rail sections of the switch structure are supported to cause the upper surfaces of the terminal portions 20 and 21 of the rails 14 and 16 to incline upwardly toward the right in Fig. 1, the incline being such that the wheels of a car moving to the right in this figure along the switch track, will be raised sufficiently 45 to ensure clearing of the main rail 11 by the flanges on the wheels and these flanges will likewise clear the main rail 11 in the movement of the car from the switch track onto the main track.

In accordance with the preferred embodiment of my invention opposed portions of the rails 12 and 13, preferably throughout their length, extend to the same height. In other words, the inclined upper surfaces of the terminal portions of the rail sections 14 and 16 have the same inclination and the remaining portions of the rail structure of the switch extend at the same height at portions thereof at opposite sides of the switch. Thus a car in passing from the main rails onto and along the switch track is maintained in hori-

zontal position in a direction crosswise of the track, as distinguished from a condition in which the car is tilted to one side or the other, this being a desirable feature as it minimizes the possibility of derailment of 70 the car.

To support the rails in the elevated position referred to I provide between these rails and ties represented at 24 and located below the rails, pillow blocks 25 secured to the ties in 75 any desirable manner as for example by spiking them thereto. In the arrangement shown the rail sections 15 and 17 only partially overlap the blocks 25 at the ends of these rail sections remote from the frog 22 and guard rail 23, the outwardly turned ends of the rail sections 14 and 16 bearing upon these blocks.

The pivotal connection of the rail sections 14 and 16 at the ends thereof just referred to, and hereinbefore mentioned, may be effected 85 in any desirable way as for example by providing plates 26 located at opposite sides of the webs of the rail sections 15 and 17, these plates being secured to these rail sections by bolts 27 and extending beyond the latter to 90 receive the web portions of the adjacent ends of the rail sections 14 and 16 which are loosely connected with these plates as by bolts 28, permitting of the desired swinging movement of 95 these rail sections.

The frog 22 comprises two main sections represented at 29 and 30 and located at opposite sides of the main rail 11. The frog section 29 is provided at its opposite lateral edges with flanges 31 and 32 to receive anchoring means hereinafter referred to and at the end farthest from the rail 11 is laterally recessed, as represented at 33, to receive the adjacent end of the rail section 16 which seats upon the bottom of this recess as shown in 105 Fig. 8 and is held in place by a bolt 34 passing through the section 29 and the web of this rail section, the upper surface of the section 29 being provided with an upwardly extending lug 35 in line with the rail section 16, the 110 upper surface of this lug at the end thereof which opposes the end of the rail section 16 being flush with the upper surface of the latter and inclining downwardly toward the main rail 11.

The frog section 29 which conformingly fits the side of the main rail 11 is provided with flanges 31 and 32 and with an angularly disposed extension 36 substantially U-shape in cross section, this yoke portion extending 120 beneath, and to a position between, the main rails 10 and 11 and presenting an upwardly opening recess 37 into which the main rail 11 extends.

The frog section 30 is recessed at the end 125 thereof remote from the main rail 11, as explained for the frog section 29, to receive and support the rail section 15 held in place by a bolt like the bolt 34, this frog section also being provided with an upwardly extending 130

lug 38 like the lug 35 to form a continuation of the rail section 15 with its downwardly tapering surface extending toward the main rail 11, the section 30 having flanges 30^a and 30^b like the flanges 31 and 32 of section 29.

The frog section 30 also comprises an angularly disposed extension 39 which extends along the inner side of the main rail 11 and into the recess 37 wherein it is disposed between this rail and the upwardly extending arm portion 40 of the yoke extension of the frog section 29.

The side of the extension 39 opposing the rail 11 is shaped to conform to the latter and its upper surface contains a wheel-flange-receiving groove 41.

The sections 29 and 30 of the frog and the rail 11 are rigidly secured together by means of a wedge bar 42 driven into the space between the extension 39 and the arm 40, the surfaces of the extension 39 and the arm 40 which are engaged by the wedge 42 being preferably recessed, as represented at 43 and 44, respectively, to receive the wedge, the inner surface of the arm 40 preferably inclining as represented more particularly in Fig. 3 to correspond with the inclination of the wedge.

The switch construction shown provides for the rolling of the wheels when opposite the space between the lugs 35 and 38 of the frog at their flange portions upon the upper surface of the frog in which movement the guard rail 23 prevents lateral displacement of the wheels ensuring the re-engagement of the tread portions of the wheels with the switch rail at the end of the frog and ensuring against accidental derailment, it being understood from the foregoing description that as a car moves from the left in Fig. 1 toward the frog, the weight of the car is transferred from the treads of the wheels at the frog side of the switch, as they leave the lug 38, to the flanges of the wheels as they pass over the frog and the intersecting rail 11, the weight of the car thereafter being transferred to the treads of the wheels as they ride upon the lug 35.

The arrangement of the parts just described is such that the transfer of the weight from the tread of the wheel to the flange thereof is effected smoothly and with the minimum jar, the upper wheel-flange-engaging bearing surface of the frog being at substantially the same elevation as the upper surface of the tread of the rail 11, the depth of the frog sections being such, as shown, that in resting directly upon the ties 24 beneath them, the wheel-flange-engaging bearing surface of the frog extends to the elevation stated.

The various rails of the structure, including the main track, are shown as secured in position by a stop clip at one side of the rail and a rotatable clip at the opposite side thereof. These stop clips represented at 45 are

of the same construction and likewise the rotatable clips represented at 46 are of the same construction for all of the rails and in addition for the frog sections, made possible by reason of the flanging of the frog sections at 31 and 32. This is very desirable inasmuch as it avoids the necessity of providing a multiplicity of forms and sizes of abutments and clips for use at different parts of the structure with consequent expense and loss of time in applying them to position.

The lugs 35 and 38 are preferably widely spaced as shown to permit, without interference, of the passage along the main track of a car provided with broad flat treads or with caterpillar tractor bars.

While I have illustrated and described a particular embodiment of my invention, I do not wish to be understood as intending to limit it thereto, as the same may be variously modified and altered without departing from the spirit of my invention.

What I claim as new, and desire to secure by Letters Patent, is:

1. A jumper frog formed of sections one of which contains an upwardly-opening recess to receive a rail and the other of which is provided with an angularly-disposed extension lying within said recess and alongside of the rail therein, and means for rigidly holding together said sections and rail.

2. A jumper frog formed of sections one of which contains an upwardly-opening recess to receive a rail and the other of which is provided with an angularly-disposed extension lying within said recess and alongside of the rail therein, and a wedge in the space between the outer side of said extension and the adjacent wall of said recess for holding together said sections and rail.

3. A jumper frog formed of sections one of which contains an upwardly-opening recess to receive a rail and the other of which is provided with an angularly-disposed extension lying within said recess and alongside of the rail therein and containing a groove in its upper surface to receive the flange of a wheel passing through the frog, and means for rigidly holding together said sections and rails.

4. In combination, a main track, a switch track, one of the rails of which is formed of spaced apart sections and extends crosswise of one of the rails of said main track, a jumper frog interposed between said rail sections and having upwardly extending tread-engaging projections at opposite sides of said main track rail, the upper surfaces of which incline downwardly toward each other, the upper surface of said frog between said projections being in a plane not below the upper surface of said main track rail, said switch rail sections extending in alignment with said projections.

5. In combination, a main track, a switch

- track one of the rails of which is formed of spaced apart sections and extends crosswise of one of the rails of said main track, a jumper frog interposed between said rail sections and having oppositely inclined upwardly extending tread-engaging projections at opposite sides of said main track rail the upper surfaces of which incline downwardly toward each other, the upper surface of said frog between said projections being in substantially the same horizontal plane as the upper surface of said main track rail, said switch rail sections extending in alignment with said projections.
- 15 6. In combination, a main track, a switch track one of the rails of which is formed of spaced apart sections and extends crosswise of one of the rails of said main track, a jumper frog interposed between said rail sections and 20 having upwardly extending tread-engaging portions at opposite sides of said track rail the upper surfaces of which incline downwardly toward each other, said frog presenting at opposite sides of said track rail and being 25 between the latter and said projections, surfaces along which the flanges of the wheels travel.
